UNITED STATES PATENT OFFICE.

ALVAH W. HALL, OF MERIDEN, CONNECTICUT.

DOUBLE-CIRCUIT INSTRUMENT.

SPECIFICATION forming part of Letters Patent No. 284,840, dated September 11, 1883.

Application filed May 17, 1883. (No model.)

To all whom it may concern:

Be it known that I, ALVAH W. HALL, a citizen of the United States, residing at Meriden, in the county of New Haven and State of Connecticut, have invented new and useful Improvements in Double-Circuit Instruments, of which the following is a specification.

This invention relates to an improvement on the well-known double-circuit instrument which is described in Reissue No. 4,493, granted to Thomas S. Hall, August 1, 1871, and which consists, essentially, of a main electro-magnet and its armature, a releasing electro-magnet and its armature, and a locking-lever controlled by the armature of the releasing electro-magnet, so that when the main electro-magnet is momentarily vitalized and its armature is attracted, a circuit through another electro-magnet is closed and retained by the locking-lever in a closed condition, after the main electro-magnet ceases to be vitalized, until the releasing electro-magnet is vitalized. With the armature-lever of the main electro-magnet is further combined a rod, which carries one or more circuit-closing springs, so that when the armature of the main electro-magnet is attracted one or more additional circuits are closed and maintained in a closed condition by the locking-lever until the releasing-magnet is vitalized.

My invention consists in the combination, with the main electro-magnet and its armature, and with the releasing-magnet, its armature, and the locking device, of two or more tappets connected to the armature-lever of the main electro-magnet, and two or more circuit-closing springs acted upon in opposite directions by said tappets, so that when the main electro-magnet is temporarily vitalized, one or more circuits, which I term the "advancing circuits," are closed and retained in this condition, and one or more other circuits, which I term the "retreating circuits," are opened and retained in this condition until the releasing-magnet is vitalized, and that when the armature of the main electro-magnet is retracted the advancing circuit or circuits (previously closed) are opened and the retreating circuit or circuits are closed, the former being retained in an open and the latter in a closed condition until the main electro-magnet is again vitalized.

In the accompanying drawings, Figure 1 represents a side view of my double-circuit instrument. Fig. 2 is a plan or top view of the same.

Similar letters indicate corresponding parts.

In the drawings, the letter A designates a base of wood or any other suitable material, on which is secured the main electro-magnet B. From said base rises a bracket, C, on which is secured the releasing-magnet D. The armature E of the main electro-magnet is secured to a lever, F, which is secured to a rock-shaft, G, mounted in standards H, and the upper end of said lever F connects by a rod, I, with a lever, J, secured to a rock-shaft, K, which is mounted in standards L. The lower end of the lever J is pivoted to a rod, M, which moves in suitable guides, N, and from which rise a series of tappets, a, b, c, d, and e.

On the base A are secured a series of springs, f g h i k l, and the corresponding anvils, f' g' h' i' k' l'.

The armature O of the releasing-magnet D is secured to a lever, P, secured to a rock-shaft, Q, which is mounted in standards R, and the rear end of the lever P is subjected to the action of a retracting-spring, S. When the main magnet is vitalized, its armature-lever F assumes the position shown in the drawings, and the armature-lever P of the releasing-magnet catches behind it and maintains the same position even after the circuit through the main electro-magnet has been broken, and said armature-lever F is not permitted to fall back until the releasing-magnet C is vitalized.

In the example shown in the drawings, the springs i k l act as retracting-springs for the armature E, the tension of said springs being greater than that of the springs f g h; but, if desired, a separate retracting-spring may be applied. Whenever the armature of the main electro-magnet is attracted, and as long as its lever F is maintained in the position shown in the drawings, the springs i k l are held in contact with their anvils i' k' l' by the tappets c d e, and circuits established through these springs are maintained in a closed position until the armature-lever F is permitted to fall back. At the same time the springs f g h are open. When the armature-lever F is permitted to fall back, the springs i k l are opened and the springs f g h are closed by the tap-

petts *a b c*, and maintained in a closed position until the main electro-magnet is again vitalized. Whenever the main electro-magnet B is vitalized, therefore, one or more circuits 5 are closed and maintained in a closed position, even after the circuit through the main electro-magnet B has been broken, until the releasing-magnet D is vitalized, and as soon as this is done the circuit or circuits which had 10 been established through the springs *i k l* are broken and one or more new circuits are established through the springs *f g h*, and maintained in a closed condition until the main electro-magnet is again vitalized.

15 I distinctly disclaim the double instrument described in Reissue No. 4,493, above named.

What I claim as new, and desire to secure by Letters Patent, is—

The combination, with the main electro-magnet and its armature, and with the releasing-magnet, its armature, and the locking device actuated by this armature, of one or more tappets connected to the armature or armature-lever of the main electro-magnet, and two or more circuit-closers acted upon in opposite directions by said tappets, substantially as and for the purpose shown and described.

In testimony whereof I have hereunto set my hand and seal in the presence of two subscribing witnesses.

ALVAH W. HALL. [L. S.]
